United States Patent Office.

J. W. RICE, OF SPRINGFIELD, MASSACHUSETTS.

Letters Patent No. 92,097, dated June 29, 1869.

IMPROVED RAILWAY-CAR BRAKE.

The Schedule referred to in these Letters Patent and making part of the same.

To all whom it may concern:

Be it known that I, J. W. RICE, of Springfield, in the county of Hampden, and State of Massachusetts, have invented a new and useful Improvement in Railroad-Car and Train Brakes; and I do hereby declare that the following is a full, clear, and exact description thereof, reference being had to the accompanying drawings, making a part of this specification, and to the letters of reference marked thereon, in which—

Figure 1 is a side elevation of a railroad-car, with my invention applied.

Figure 2 is an end view of the same, showing the general arrangement of the drum, brake-shafts, levers, and the cords operating the same.

Figure 3 is a plan view of the trucks of the car, with the levers attached to the bottom of the car, showing the general arrangement of the brakes, brake-rods, chains, &c., as in operation.

Figure 4 is an enlarged view of the drum-gear and staff for operating the drum, levers, &c., all of which are used to apply and release the brakes throughout the train simultaneously.

Figure 5 is another view of the same, showing the operation of the levers.

Figures 6 and 7 show a horizontal transverse section through line R S of fig. 5, representing the different positions of the pawl, or dog which engages with the ratchet-teeth upon the drum containing the spring.

Figure 8 is a horizontal transverse section through line T U of fig. 4, showing the dog which operates the ratchet connected with the inner end of the spring in the drum.

Figure 9 is a plan view of the single equalizing-lever, or the equalizer used in operating the brakes of a single car.

Figure 10 is a side view of the same.

Figure 11 is a plan view of a portion of the same, showing the chain and loose pulleys.

Figures 12 and 13 represent a side view and plan of the double equalizing-lever, or the equalizer used in operating the brakes of more than one car.

My invention relates to a braké to be used for stopping or decreasing the speed of a train of railroad-cars when in motion; and

It consists of an improvement in the arrangement of a spring within a drum, or case, with a brake-staff and gear for operating the same, together with pawls, or dogs, and ratchet wheels, levers, and cords for operating said levers, whereby any one person may, by pulling the cords, apply the brakes to all the cars of the train simultaneously, and also release them in case of necessity, this said arrangement being an improvement upon the device for which Letters Patent of the United States were granted me, dated the 23d day of April, A. D. 1867; and

My invention also consists of an arrangement of equalizing-levers with the chains and rods of a brake, whereby one person may operate the brakes upon two cars or more at the same time, so that a less number of brakemen will be required upon the train than is required for the operation of the brakes now commonly used.

That others skilled in the art may be able to make and use my invention, I will proceed to describe its construction and the mode of its operation.

In the drawings—

A B C represent the frame of a car, the ends of the pieces C projecting beyond the posts B, forming the usual platform at each end of a car.

The posts, or rods y y, are attached to the end of the platform, and the plates a and a' are secured to the said posts y y.

The plates a and a' furnish a bearing for the shaft a', and for the upper end of the shaft a', the lower end of said shaft a' having a socket therein, into which fits, somewhat loosely, the upper end of the spindle n, which passes down through the block c, and serving as a pivot upon which turn the pawls L and L', slots, x and x', being made in said block c, in which the pawls L and L' operate, in a horizontal manner, upon said pivot n.

Vertical slots, x' and x', are made in the block c, and the levers b' and b', which are pivoted, at o', to the projecting pieces o', have their short ends bent upward, extending through the aperture e' and vertical slots in the block c, the end e' of the lever b' extending sufficiently upward to prevent the pawl L' from moving outward, when the long arm of said lever is down, as shown in fig. 6; and the short end e' of the lever b', extends upward sufficiently to prevent the pawl L from moving outward, when the long arm of the said lever is down, as shown in black lines in fig. 8.

The pawl L' has a knuckle-joint, or is jointed at its middle part, so that when the inclined sides of the teeth of the ratchet a' pass in contact with the curved side of the end e' of said pawl L', the joint is opened, and the drum, having the ratchet-teeth a' thereon, is permitted to turn in that direction, the spring c', operating to keep the joint closed when the inclined sides of the teeth a' are not bearing against the pawl L'.

The rods b and b' are attached to the long arms of the levers b' and b', and pass up through apertures in the plates a and a', or other guides for that purpose.

The operation of this arrangement may at first sight appear to be like that shown in said Letters Patent granted to me, as hereinbefore mentioned, but upon reference to the same, it will be seen that the shaft which passed through the drum containing the spring, extended above the upper plate or rail, and a hand-wheel was attached thereto, by means of which the

brakes were applied as in the ordinary manner. In that combination of the ordinary hand-brake with the self-acting brake, it was found that by its use the life of the brakeman was endangered, as he might be just in the act of seizing the hand-wheel to apply the brakes, as the engineer pulled the cord to apply the self-acting brake, which might either injure his hands, or possibly throw him off the train.

It will be seen, that in the present arrangement, the shaft a^2 , which passes through the drum, does not extend above the upper plate, or rail a , and that the wheel, or winch upon the winding-shaft a^1 , cannot be used to apply the brakes in the ordinary manner, the shaft and wheel c^2 upon the other side of the platform being used for that purpose, and has no connection with the self-acting apparatus. This brake-shaft c^2 , to be used in the ordinary method of applying the brakes, is shown in fig. 2.

The lower ratchet-wheel, a^3 , has a sleeve, n^3 , attached thereto, said sleeve passing up through the drum a^1 , which contains a coil spring, similar to that shown in the hereinbefore-mentioned Letters Patent, one end of this spring being attached to the said sleeve n^3 , at d^1 , while the other and outer end of the spring is attached to the drum, at d^2 .

The lower wheel has the teeth o thereon, while the ratchet-teeth a^4 are made upon the drum a^1 , and the drum being open at the top, the spring d is placed therein and secured, and the cap a^5 , having the gear-teeth a^6 upon its periphery, and the ratchet-teeth a^4 upon the top, is placed over the top of the drum a^1 , and is secured thereon by means of set-screws, or by any other suitable means. The shaft a^2 passes down through the sleeve thus inserted in the drum, the lower end of said shaft resting, or having a bearing in the step c , the brake-chain being attached to the lower end of said shaft.

A pawl, o' , with its lever a^7 , is attached directly to the shaft a^2 , above the cap a^5 , said pawl engaging with the ratchet-teeth upon the top of said cap a^5 .

A cord, b^4 , extends through the entire length of the train, in the upper part of the cars, passing over pulleys, b^1 , said pulleys being placed in the upper part of the cars, and just over the rods b b^1 , that part of the cord which is between the two pulleys at each end of the car, passing down and through the loop s^1 , at the upper end of the rod b^1 , the end of the cord at the rear end of the train being secured to some part of the car, while the end of the cord at the forward end of the train may be attached to some part of the engine, within easy reach of the engineer.

It might be well to have a small cylinder, of sufficient size, attached to the cab of the engine, and operated, or made to revolve by means of a spring, and the front end of the cord attached to the said cylinder, so that if the engineer should deem it necessary to apply the train, or self-acting brake, he could do so by simply releasing a spring.

A cord, b^5 , also extending the entire length of the train, so placed as to be out of the reach of passengers, and passing over and down between two pulleys placed over the rods b , and through the loop in the top of the said rod b , serves to release the brakes, when they are applied, when the danger is past, or the train is again put in motion after stopping.

The staff a^1 has a bearing in the upper plate a , the spindle n entering the socket in the lower end of said staff; and upon the lower end of said staff is securely fixed a gear-wheel, the teeth of which engage with the teeth a^4 , upon the cap a^5 , and the staff a^1 extends above the upper plate a , and has a hand-wheel, or winch at the top.

A small piece, e , is pivoted to the top of the block c , to hold the shaft up, so that the teeth a^4 may engage with the teeth a^6 , when the said piece e is swung un-

der the gear-wheel a^6 ; but when said piece e is swung out from under the wheel a^6 , the shaft a^1 then drops down, so that the gear-wheel a^6 rests upon the top of the block c , and the two wheels a^4 and a^6 are then out of gear.

The end c' of the brake-chain is attached to the lower end of the brake-staff a^2 , and passes back to about the middle of the car, passes over the pulley s^1 , and is attached to the end f^1 of the equalizing-lever O . This lever is the same substantially as that shown in the Letters Patent hereinbefore mentioned as granted to me, and requires no further explanation here.

The chain f^2 , one end of which is secured to the upper end of the brake-lever h , passes around the pulleys of the equalizer O , as shown in fig. 3, the other end of said chain being secured to the upper end of the brake-lever h^1 . These brake-levers h and h^1 are also more fully described in said Letters Patent before mentioned.

To the bottom of the car is attached a proper piece, s^1 , with a pin, s^2 , passing through it, and into the frame-work of the bottom of the car, or into a piece of iron attached thereto.

This pin s^2 also passes through the equalizing-lever h^2 , said lever having two loose pulleys thereon, one at each end, or near each end.

The brake-chain f^3 , which is operated by this lever, is attached, at one end, to the end f^7 of the equalizing-lever O , passing back to the lever h^2 , and around the pulley n^6 , thence longitudinally along the lever h^2 , and to the other side of it, and around the loose pulley n^7 ; and thence extending to the next car, the other end of said chain being attached to another equalizing-lever, O , upon the other car; or before being attached to the said lever, it may pass around the pulleys of another equalizer, h^5 , upon said other car.

In either case, it is believed that the brakes would be equally operative, but it might be found preferable to have two equalizers, like those shown in fig. 3, upon each car.

The common brake-staff r is attached to the platform of the car, in the usual manner, to the lower end of which staff, is attached the brake-chain f^4 , the other end of said chain being attached to the end of the lever h^5 .

It will be perceived that the lever O has holes therein, at different distances from each end, so that the leverage may be lengthened or shortened as may be desired, by attaching the chains to said lever at these holes.

The chain f^5 has a long link, h^6 , at the middle of the lever h^5 , through which link the pin h^7 passes, so that in case the chain breaks, the end of the link will pull against the said pin in either direction, and one of the brakes will not fail to operate in case the chain becomes temporarily broken.

The same effect is produced in the lever O , by a pin, i , passing through the lever, and also through a link of the chain, said pin sliding in an oblique slot in the lever.

The middle portion of said lever O may be made of two parallel plates, with loose pulleys between, and the arms f^1 and f^7 secured to said plates by means of bolts, said bolts also serving as pivots, upon which the loose pulleys operate, as shown in figs. 10 and 11.

Having thus described the construction of my invention, I will now proceed to describe its mode of operation.

All the parts being in place, as described, the pawls L and L' are placed in position, as shown in black lines in figs. 6 and 8, and the levers b^2 and b^3 in position shown in fig. 4, with their bent upright ends e^4 and e^5 within the block c , passing up by the outside

of the rear end of each pawl L and L', as shown in black lines in fig. 5.

The piece e being under the pinion a⁶, keeping the shaft a¹ up in the position shown in fig. 4, the said shaft a¹ is rotated in the proper direction, by means of the wheel or winch at the top, and the two gears a⁴ and a⁶ engaging with each other.

The drum a⁵, with its cap a⁶, is made to revolve in the direction indicated by the arrow, carrying with it the outer end of the spring within the drum, as said end is secured to the drum.

When the rotating of the drum commences, the sleeve n³, with the ratchet a⁸ attached thereto, is, by the action of the spring, made to rotate in the direction of the arrow, as shown in fig. 8, until one of the teeth o strikes against the end e¹ of the pawl L, and as the said pawl is held securely in that position by the end e¹ of the lever b², the said sleeve and ratchet-wheel a⁸ is prevented from making any further rotary movement, and the inner end of the spring is held stationary by the sleeve n³, while the outer end of the spring is carried around with the drum, until the said spring has been coiled up sufficiently to accumulate enough power to apply the brake.

When the spring and drum have been rotated sufficiently, the piece e is swung upon its pivot out from under the pinion a⁶, and the shaft a¹ dropped, so that the pinion a⁶ rests upon the block e.

The apparatus is now ready to be used in applying the brakes.

If the cords b⁴ and b⁵ are all connected through the train, and also with the engine, within reach of the engineer, if he should deem it necessary to stop the train suddenly, by pulling the cord b⁴, or causing it to be pulled, by releasing a spring, as hereinbefore described, the rods b¹ through the train are pulled upward, raising the long arm of the lever b³ up against the bottom of the lower plate a⁹, and drawing the short upright end e² of the lever away from the side of the pawl L', which has been in the position shown in black lines in fig. 6, while the spring remained coiled tightly, or while the drum was in a position ready for use.

This withdrawal of said short end of the lever from the side of said pawl, permits the said pawl to fly to one side quickly by the pressure of the ratchet-teeth a⁵ against it, into the position represented in fig. 7, when the drum rotates rapidly in an opposite direction, caused by the partial uncoiling of the spring within.

When the drum, with its cap a⁶ attached thereto, was being rotated, by turning the shaft a¹ in coiling up the spring, the ratchet-teeth a⁵ on the top of the said cap, passed along under the loose pawl o¹ pivoted to the stud a⁸, the end of said pawl sliding along up each incline, and dropping down each tooth, and when the drum is permitted to fly back, by disengaging the pawl L' from the teeth a⁵, the ratchet-teeth a⁵ upon the cap strike against the end of the loose pawl o¹, carrying it and the shaft a¹ to which the pawl is attached around with it, winding the chain e' around the lower end of said shaft a¹.

This draws the end f¹ of the lever O back toward the pulley s³ on the bottom of the car, causing the chain f³ to be shortened, bringing the brake-shoes against the wheels; and as this is done upon all the cars of the train at the same instant, by the same cord b⁴, the train may be stopped very quickly.

The brakeman may also be using the ordinary hand-brakes c¹ at the same time, without danger of harm.

In this operation of applying the brakes, the inner end of the spring has been held stationary by the sleeve n³ and ratchet-wheel a⁸ and pawl L.

After the danger is past, and it is desired to put

the train in motion, the cord b⁵ is pulled, raising the long arm of the lever b² into a similar position to that shown in fig. 5, when the pawl L flies out to one side, as shown in red lines in fig. 8, by the pressure of the teeth o against said pawl, and the inner end of the spring being released by the rotation of the sleeve n³, the spring is free to uncoil itself, thus removing the power which holds the brake-shoes to the wheels.

The hand-brake shaft c² is placed at the other side of the platform, and one end of the chain f is attached to its lower end, the other end of said chain being attached to the end f¹ of the lever O.

This arrangement brings into use the equalizing-lever O in applying the brakes of the car, whether applied by means of the hand-brake shaft c², the double brake-shaft r, or the self-acting apparatus of the drum and spring, either used separately or all at the same time.

If it should be desired to apply the brakes to two or more cars at the same time, with only one person to operate the brakes, it may be done by turning the shaft r, thus drawing back the end n⁶ of the equalizing-lever h⁶, and shortening the chain f³.

This shortening of the said chain draws back the end f¹ of the lever O, and applies the brakes to one car, while the other end of the chain f³, being attached to the levers on the next car, operates the brakes upon the said next car in precisely the same manner, the link h⁶ and pin h⁷ operating to apply the brakes upon one car, if the chain should be temporarily broken, as hereinbefore described.

I am aware that self-acting brakes have heretofore been used, and applied by means of a spring confined within a drum, as shown in Letters Patent, No. 64,036, granted to me, and dated the 23d day of April, A. D. 1867, (wherein is shown also the equalizer O,) and also in Letters Patent, No. 16,004, granted to William G. Cramer, and dated the 4th day of November, A. D. 1856; and I am also aware that an arrangement of cords for operating the same is described in both said Letters Patent; and I do not claim any of the said devices, nor any part of the same, separately considered, or when considered irrespective of my arrangement and construction, as herein described; but having described my invention or improvement,

What I do claim as new, and desire to secure by Letters Patent, is—

1. The combination of the drum a⁵ and cap a⁶, ratchet a⁸, and sleeve n³, shaft a¹ with its pawl o¹, the shaft n¹, pawls L and L', and levers b² b³, as a means of applying and releasing the brakes of a railway-car, automatically, all constructed and operating substantially as herein described.

2. The swinging block e, when used in connection with the winding-shaft a¹, having a socket in its lower end, and the spindle n, as a means of changing the vertical position of said shaft a¹ with its pinion a⁶, substantially as described.

3. In a self-acting car-brake, the levers b² b³ pivoted at o¹, in combination with the pawls L and L', all constructed and operating substantially as described.

4. The cords b⁴ and b⁵, passing down between two pulleys, and through a loop or ring in the rods b and b¹, as a means of applying and releasing the brakes of a train or series of railway-cars simultaneously, substantially as described.

5. The combination of the chains f, o¹, and f³, with the equalizing-lever O, whereby the hand-brake staff c and self-acting brake-drum may be used in applying the brakes of a car, either separately or together, substantially as described.

6. The combination of the chains f⁶, f⁵, and f³,

with the equalizing-levers h^2 and O , as a means of applying the brakes of two or more cars at the same time, by the operation of one hand-brake staff, r , substantially as herein described.

7. A brake-lever, O , having a series of holes near each end, for the purpose of changing the leverage-

power of the brake when desirable, constructed substantially as herein described.
